UNITED STATES PATENT OFFICE.

ALEXANDER NELSON, OF NEWARK, NEW JERSEY, AND BENJAMIN B. AVERY, OF NEW YORK, N. Y., ASSIGNEES, BY MESNE ASSIGNMENTS, TO GERMPROOF CUP CORPORATION, OF NEW YORK, N. Y., A CORPORATION OF NEW YORK.

FORMER FOR MANUFACTURING SANITARY DRINKING-CUPS.

1,341,833.

Specification of Letters Patent.

Patented June 1, 1920.

Application filed April 4, 1918. Serial No. 226,594.

To all whom it may concern:

Be it known that we, ALEXANDER NELSON and BENJAMIN B. AVERY, citizens of the United States, residing at Newark, Essex county, State of New Jersey, and New York city, county and State of New York, respectively, have invented certain new and useful Improvements in Formers for Manufacturing Sanitary Drinking-Cups, of which

10 the following is a specification.

This invention relates to the manufacture of sanitary drinking cups, the object thereof being to provide an improved former for folding the side edges of a cup blank a plurality of times thereby to hold such side edges against separation, one of the objects of the invention being to provide an improved cup blank former whereby the use of feeding and pressure rollers for folding 20 and feeding the edges of the cup blank may be done away with and a much simplified as well as efficient cup blank folding means provided.

In the drawings accompanying and forming a part of this specification, Figure 1 illustrates a portion of a web of paper severed to form a cup blank. In practice however, the cup blanks are formed from a continuous web of paper carried by a roll, and 25 each blank is severed as it passes through the machine for the purpose of forming the cup; Fig. 2 is a perspective view of a cup folded from the blank with the locking flap unfolded; Fig. 3 is a perspective view of 30 the completed cup; Fig. 4 is a view of part of the machine illustrating the former in position and the manner in which the cup is fed thereto and therefrom; Fig. 5 is a cross-sectional view taken on the line 5—5 Fig. 4; Fig. 6 is a cross-sectional view taken on the line 6—6 Fig. 4;—these two views illustrating different positions of the folded edges of the cup blank as it passes through the former; Fig. 7 is a top view of one of the 45 former members; Fig. 8 is a face view of the former member shown in Fig. 7; Fig. 9 is a top view of the other former member; and Fig. 10 is a face view of the former member shown in Fig. 9.

50 Similar characters of reference indicate corresponding parts in the several figures of the drawings.

The present improved former comprises a pair of members 10 and 11. The member

10 comprises what may be considered herein as the outside member and is provided with a curved apron-formed portion 12 for directing and guiding one end of the cup blank. This apron 12 extends transversely or at an angle to the former portion proper 60 of the member 10 and is preferably formed integral therewith. The member 10 comprises a flat back portion 13, each side edge of which is curled inwardly as at 14, which curl gradually increases toward the bottom 65 of the member 10, at which point the edge of the former is practically folded upon itself twice, such folds being suitably spaced for the passage of the blank edges whereby the curled edges of the blank may be said 70 to taper from their upper ends to their lower ends, so that they somewhat resemble the curled petals of some well known flowers. The other member 11 of the former likewise comprises a transversely extending 75 shelf portion 15 and a plate portion 16 having its side edges bent inwardly as at 17 for a part of the height of the plate and cut away as at 18, so that the width of the plate is less at the lower portion thereof than at 80 the upper. The member 11 has its inwardly bent side edges 17 so formed as to fit within the curled side edges of the member 10 in such position that a blank will pass between the plate portions 13 and 16 of the two 85 formers and have its edges guided by the bent and curled side edges of the formers in such manner as to fold the same twice and thus lock the side edges of the blank to form the cup. In other words in such manner 90 that the side edges of the blank will be folded and infolded when the blank passes between the two formers in a manner which will be readily understood. The former is suitably positioned in the machine and when 95 a cup blank 50 has been severed from its web, it is fed downwardly in the manner shown in Fig. 4 by a suitable reciprocating plunger or folder blade 60, which engages and folds the cup blank at a certain point 100 transversely of its length and forces the so folded cup blank down into the former after one end of the cup blank is guided up the apron 12 in the manner shown in Fig. 4. When the folded cup blank has sufficiently 105 passed through the former, its lower end is engaged by a pair of rollers 70, which pull the folded cup blank through the former.

As the cup blank passes through the former the side edges of the blank are caused to pass into the curled portions thereof thereby to fold and infold such side edges 5 in the manner shown. It will of course be understood that the folder blade 60 is reciprocated up and down by any suitable means. In practice the curled edges of the former are sufficiently close together to compress 10 the folded side edges of the blank as the side edges are folded during the passage of the blank through the former, and as they pass between the roller 70 these side edges are suitably crimped. When the cup blank has 15 passed between the roller 70 a suitable reciprocating tucker 80 operated by any suitable means moves in position to engage the flap portion 51 of the blank and force it between one of the rolls 70 and a companion roll 71 20 whereby this flap is bent over the rear of the cup in the manner shown in Fig. 3 thereby to form a lock for the side edges as well as a smooth mouth edge for the cup.

In carrying out this improved method of 25 making sanitary drinking cups, the web of paper or other thin material either of paraffin paper or otherwise, as may be found desirable, is conveyed into position and suitably severed transversely thereof to provide 30 a cup blank 50, which is then folded along the line 52 and substantially midway of its length excluding the flap portion 51 by the reciprocating folder blade 60. This folder blade reciprocates to carry the cup blank sufficiently far into the former so that 35 the lower end thereof will be engaged by the two sets of rollers 70, which work only along the side edges of the cup. As the cup blank is fed through the former the side edges 40 thereof are folded and infolded by the curled edge of the former member 10 around the guiding side edges 17 of the former member 16, thereby to produce a sanitary drinking cup without the use of pressure 45 or feeding rollers, as heretofore found necessary. The folding blade 60 not only transversely folds the cup blank but also constitutes a means for pressing or pushing the blank into the former sufficiently far to enable 50 the forward end thereof to be engaged by the roller 70 by reason of the fact that the folder exerts its pressure upon the transverse fold of the cup blank.

It will be understood that the various details 55 may be more or less changed without departing from the spirit or scope of the present improvement.

We claim as our invention:

1. A former for a sanitary drinking cup 60 comprising a pair of spaced parallel plates, said plates having spaced-apart side edges, one having its side edges folded upon itself a plurality of times and thereby curled at each side thereof and coöperating with the 65 side edges of its companion plate.

2. A former for a sanitary drinking cup comprising a pair of spaced parallel plates, said plates having spaced-apart side edges, one having its side edges folded upon itself a plurality of times and thereby curled at 70 each side thereof with a gradually increasing curl and coöperating with the side edges of its companion plate.

3. A former for a sanitary drinking cup 75 comprising a pair of spaced plates, one of said plates having spaced-apart side edges curled upon itself at each side thereof, the other of said plates having bent side edges located within the curled portions of said first plate and forming guiding means for a 80 cup blank.

4. A former for a sanitary drinking cup comprising a pair of spaced plates, one of said plates having spaced-apart side edges curled upon itself at each side thereof with 85 a gradually increasing curl, the other of said plates having bent side edges located within the curled portions of said first plate and forming guiding means for the cup blank.

5. A former for a sanitary drinking cup 90 comprising a pair of spaced blades, one having a curved apron and one having curled side edges, and one of said plates having bent guiding edges located within said 95 curled side edges.

6. A former for a sanitary drinking cup comprising a pair of spaced plates, one having a curved apron and one having curled side edges, and one of said plates having bent guiding edges located within said 100 curled side edges, the curl of the side edges of one plate gradually increasing toward one end of the plate thereby to fold and infold the side edges of the cup blank.

7. A former comprising a pair of spaced 105 plates, each having a transversely projecting portion at its upper end, one of said plates having bent side edges to form guiding edges and the other of said plates having gradually increasing curled side edges 110 adapted to overlap the guiding edges of its companion plate.

8. A former comprising a pair of spaced plates, each having a transversely projecting portion at its upper end, one of said 115 plates having bent side edges to form guiding edges and the other of said plates having gradually increasing curled side edges adapted to overlap the guiding edges of its companion plate, said first plate having 120 cut-away portions below its bent side edges.

9. A former comprising a pair of spaced plates, one having bent side edges forming guides and cut-away portions below such guides and the other having curled side 125 edges, the curl of which gradually increases toward one end thereof, and adapted to overlap the guiding edges of said first plate.

10. A former for a sanitary drinking cup comprising a pair of spaced plates, one of 130

said plates having each of its side edges folded upon itself a plurality of times and thereby curled and the other of said plates having bent side edges located within the 5 curled portions of said first plate and forming guiding means for a cup blank.

11. A former for a sanitary drinking cup comprising a pair of spaced parallel plates, one of said plates having each of its side 10 edges folded inwardly toward the center line of the plate, and then away therefrom and coöoperating at its folded side edges with its companion plate.

12. A former for a sanitary drinking cup comprising a pair of spaced parallel plates, 15 one of said plates having each of its side edges folded inwardly toward the center line of the plate, and then away therefrom, and the other of said plates having bent sides located within the folded edges of said first 20 plate and forming guiding means for a cup blank.

Signed at New York city, New York, this 26th day of March, 1918.

ALEXANDER NELSON.
BENJAMIN B. AVERY.
